CUTTER FOR WELL DRILLS

Floyd L. Scott, Houston, Tex., and Herman A. Schaeffer, Los Angeles, Calif., assignors to Hughes Tool Company, Houston, Tex., a corporation of Texas

Application March 9, 1935, Serial No. 10,254

7 Claims. (Cl. 255—71)

Our invention relates to well drills and more particularly to hard formation drills which are intended to drill upon rock and other hard formation and employing cutters of a general conical shape adapted to surround the ends of the shafts 5 upon which they are mounted.

This general type of bit is now old in the art. The invention resides in the particular construction of the cutting surface of the cutters employed 10 and the position in which they are placed relative to each other upon the lower end of the bit.

An important object of the invention is the provision of cutting teeth upon the outer surface 15 of the cutters which are formed to cut separate and different imprints upon the bottom of the hole, no two cutters having teeth which may track in the impressions on the bottom of the hole made by the teeth of the other cones.

It is another object of the invention to provide 20 teeth arranged toward the smaller ends of the cutters to cut effectively upon the bottom of the hole by a combined scraping and chisel action.

It is a further object of the invention to mount 25 the cutters in an offset position relative to each other so that a true rolling action of the conical cutters is prevented thereby giving a scraping as well as a chisel action to all of the cutting area of the cutters.

In the drawing herewith Fig. 1 is a side elevation 30 of a well drill employing the invention.

Fig. 2 is a bottom plan view showing the cutters 35 detached from the head but arranged in operating position so that the operation of the cutters may be better understood.

The head upon which the cutters are mounted 40 is of ordinary construction having an upwardly tapered shank 1 thereon for attachment to the usual drill collar or coupling member. There are in this modification three downwardly extending legs 2 formed upon the cutter head. Each of these legs has an inwardly flattened face at 3 from 45 which the shafts extend to support the cutters 4. This supporting structure is old in the art and need not be shown in detail.

The formation of the cutters which forms the subject matter of this improvement is shown best 50 in Fig. 2. I have shown three of these cutters mounted upon their supports in an offset position relative to each other and to the axis of the drill. In other words, the central longitudinal axis of each cutter is pointed in a direction tangent to a circle about the central axis. Each cutter is provided with an outer row of teeth 55 which are numbered on the three cones by the numerals 4, 5 and 6. The teeth 4 on the par-

ticular cutter shown are not directed in a line longitudinally of the axis of the cutter but are inclined with the inner end of each tooth inclined forwardly toward the direction of rotation of the bit head, said bit rotating in the direction of the arrow in Fig. 2. The teeth 5 are inclined in the opposite direction, the forward end of the teeth being directed rearwardly away from the direction of rotation. On the remaining cutter the teeth 6 are cut longitudinally of the cutter 10 and are directed toward the apex of the cone. Thus these outer rows of teeth 4, 5 and 6 on the different cutters will engage the bottom of the hole, the teeth 4 and 5 cutting an X-shaped impression upon the rock and the cutter 6 forming 15 a line directly across it, each of them cutting a slightly different portion of the bottom, making it impossible for the outer rows of teeth on the three cutters to track on the bottom of the hole as is the usual tendency in bits of this character. 20

Adjacent the outer row of teeth on each cutter is an inner row which are numbered 7, 8 and 9 on the three separate cutters. The cutter having the teeth 7 thereon has the crests of the teeth directed rearwardly from the direction of rotation; the teeth 8 are directed forwardly in the direction of rotation at their inner ends and the teeth 9 on the remaining cone are cut radially of the cone. Thus in this second row of teeth the marks left by the crests of the teeth upon the 30 well bottom will form impressions similar to those on the outer row but the notches upon the well bottom cut by the teeth 7 and 8 are in the direction reverse to those of the outer rows of teeth. It is to be noted that the two outer rows of teeth 35 are separated from each other by a cleft or notch 10, which is approximately spiral, that is, the teeth as shown in the row 6 in Fig. 2 is started at one point upon the crest of the teeth and is extended around the cone in a spiral direction, 40 so that when the entire circumference of the cone has been cut the groove is of general spiral form, as will be obvious from the drawing.

Forwardly on the cone from the two outer rows of teeth are a plurality of rows of teeth 11. These 45 rows of teeth have a crest 12 which runs circumferentially around the cone but in a spiral rather than truly circumferential direction. The axis of this spiral tooth with crest 12 is inclined toward the apex of the cone, making each row of teeth 50 somewhat saucer-shaped so that they will have the action upon the well bottom of a disc plow. The crests of the spiral cutting edges are notched and at the end of the spiral are forwardly projecting spear points or teeth 13 formed to cut 55

the center of the hole and prevent the formation of a core upon the well bottom at that point. These points 13 are designed so that the three points acting together will cut the full center of the hole.

5. In the operation of these cutters the action will be approximately as already set forth. The outer rows of teeth will each cut a shallow notch or chisel-shaped impression upon the bottom of the hole at a different angle from the impression made by the preceding or succeeding outer rows. The inner spiral rows of teeth upon each cutter are moved about the center of the hole with a combined rolling and scraping action which tends 10 to plow the bottom of the hole with the forward cutting crest 12 upon each tooth. This effects the cutting of the central portion of the hole in the most efficient manner. The arrangement of the three cutters is such that they will each cut an 15 independent track upon the bottom of the hole, serving to prevent the tendency in bits of this character to form notches in the well bottom into which the corresponding teeth of all of the cutters engage. Tracking is directly avoided and a 20 most efficient cutting action obtained due to the independent action of each tooth in engaging the well bottom.

What we claim as new is:

1. In a well drill, a head, three approximately 30 conical shaped cutters mounted on the forward end of said head to roll upon the bottom of the hole being drilled, each of said cutters having its longitudinal axes directed to one side of the central axis of the drill, teeth at the bases of said 35 cutters having chisel shaped edges, the corresponding rows of teeth adjacent the base on each cutter having crests inclined relative to the cutter axis in a direction different from the direction of those on adjacent cutters, and teeth on each cutter adjacent the apex thereof having cutting edges extending around the cone and their cross sectional axes inclined toward the central axis of said drill.

2. In a well drill, a head, three approximately 45 conical shaped cutters mounted on the forward end of said head to roll upon the bottom of the hole being drilled, each of said cutters having its longitudinal axes directed to one side of the central axis of the drill, teeth at the bases of said 50 cutters having chisel shaped edges inclined relative to the cutter axis in a direction different from those on adjacent cutters, and teeth on each cutter adjacent the apex thereof having cutting edges extending spirally around the periphery of the cone with their cross sectional axes inclined toward the center of said hole.

3. In a well drill, a head, three approximately 60 conical shaped cutters mounted on the forward end of said head to roll upon the bottom of the hole being drilled, each of said cutters having its longitudinal axes directed to one side of the central axis of the drill, teeth at the bases of said 65 cutters having chisel shaped edges, the corresponding rows of teeth adjacent the base on each cutter having crests extending approximately longitudinally of the conical surface and inclined relative to its axis in a direction different from those on adjacent cutters, and teeth on each

cutter adjacent the apex thereof having their axes inclined toward the center of the hole.

4. In a well drill, a head, a plurality of approximately conical shaped cutters mounted at the forward end of said head to roll upon the bottom of the hole being drilled, two rows of teeth adjacent the base on two of said cutters extending approximately longitudinally of the conical surface but the crest of the teeth in each of said two rows on each of said two cutters being formed 10 to make a cut on the bottom of the hole inclined in a different direction with respect to radius of the hole from that of the other row on the same or on adjacent cutters so that the corresponding teeth on one cutter will not track in the cuts 15 formed by adjacent cutters, and teeth on each cutter toward the apex thereof having their crests extending in an approximately circumferential direction about the surface of the cutter.

5. In a well drill, a head, a plurality of approximately conical shaped cutters mounted at the forward end of said head to roll upon the bottom of the hole being drilled, said cutters being positioned with their longitudinal axes offset relative to the central axis of the drill to obtain 20 a partial scraping action, a spirally inclined outer row of teeth at the base of each cutter having their crests of chisel shape and formed, on the cutter to cut tracks on the well bottom directed inwardly from the wall of the well at different 30 angles, and a spiral row of teeth between said outer row of teeth and the apex of each cutter, the crests of which extend approximately circumferentially of the cone and their axes inclined toward the central axis of said head to engage 35 the well bottom with a plowing action.

6. In a well drill, a head, a plurality of approximately conical shaped cutters mounted at the forward end of said head to roll upon the bottom of the hole being drilled, said cutters being positioned with their longitudinal axes offset relative to the central axis of the drill to obtain 40 a partial scraping action, a spirally inclined outer row of teeth at the base of each cutter having their crests of chisel shape and formed on the 45 cutter to cut tracks on the well bottom directed inwardly from the wall of the well at various angles so that the said tracks cannot coincide, and a row of teeth extending spirally about each cutter from said outer row to the apex and having 50 cutting edges thereon approximately circumferentially of the cutters.

7. In a well drill, a head, a plurality of approximately conical shaped cutters mounted on the forward end of said head to roll upon the 55 bottom of the hole being drilled, two outer rows of chisel-shaped teeth extending circumferentially about the base of each cutter, the crests of the teeth in each row on each cutter extending in a different direction relative to the longitudinal axis of the cutter from that of the crests of teeth on the adjacent row, the direction of inclination of the said crests of teeth on each cutter being varied, so that the teeth of each row on each cutter will cut a separate impression 60 upon the well bottom.
